OIL WELL CHOKE VALVE

Aubrey L. Stewart, Tulsa, Okla., and Charles M. Laundermilk, Shreveport, La.

Application October 25, 1941, Serial No. 416,558

6 Claims. (Cl. 277—53)

The invention relates to choke valves for oil wells, and has for its object to provide a device of this character adapted to be mounted on the Christmas tree, and comprising a casing having a valve seat plug therein having horizontal circumferentially arranged ports of different size and with a central port of the size of the maximum flow, and any number or combination of said ports being adapted to be opened according to the amount of flow desired.

A further object is to provide a port extending transversely across the plug and through the valve casing and through which transverse port various instruments may be passed into the well or blasting bombs when the central valve is retracted and pressure substantially cut off and exhausted from the casing.

A further object is to provide a gauge and scale means in connection with the central maximum flow valve for indicating the amount of flow therethrough, and to provide the casing, adjacent the fractional needle valve, with indicia indicating the size of the ports in the plug controlled thereby.

A further object is to interpose the device between the master valve and the separator line valve so that pressure and back pressure can be cut off from the device and to provide means whereby pressure trapped in the casing can be exhausted to the atmosphere preparatory to an instrument inserting operation through the device.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a vertical longitudinal sectional view through the multiple choke valve.

Figure 2 is a front elevation of the choke valve.

Figure 3 is a front elevation of the choke valve with the cover plate removed along with its needle valve.

Figure 4 is a perspective view of the cover plate and the various valves carried thereby.

Figure 5 is a perspective view partially in section showing the interior structure.

Figure 6 is a view similar to Figure 1, but showing the gauge structure removed and an attachment applied for lowering a bomb into the well.

Referring to the drawings, the numeral 1 des-

ignates a conventional form of well casing or portion of a Christmas tree and 2 the master valve thereon. Secured to the upper end of the master valve casing 3 by means of bolts 4 is the choke valve housing 5. Pressed into the chamber 6 of the housing 5 is a tapered plug 7 having a chamber 8 therein in communication with the chamber 9 of the master valve casing 3 through the port 10. The port 10 is in alignment with a second port 11, clearly shown in Figure 1 and with a port 12 in the upper side of the housing 5, the purpose of which will presently appear. The plug 7 is provided with a plurality of ports 13, longitudinally extending and concentrically arranged. All of the ports 13 are of different diameters, preferably from one eighth to one inch, as indicated in Figure 2, and adapted to be selectively opened, singularly or in combination for allowing flow of predetermined amount from the well casing through port 10, chamber 8, right hand side of chamber 6 and into the left hand side 6a of the chamber so it can be delivered through the pipe 14 to a separator when the valve 15 is opened. The plug 7 is provided with an axial needle valve seat 16, preferably of a size to allow flow of full capacity, usually two inches, and cooperating with the seat 16 is a needle valve 17, the shank 18 of which extends outwardly through the cover plate 19, and is provided with an indicator 20 cooperating with a scale 21.

The cover plate 19 also has mounted therein needle valves 22 which cooperate with valve seats 23 at the right hand ends of the various ports 13. The valves 22 have their stems threaded at 24 in the cover plate 19 and extend through glands 25 and terminate in angular heads 26 adapted to receive a wrench for opening and closing the same.

It will be seen that by manipulating the various needle valves any fractional part of the capacity may be allowed to pass and when desired the needle valve 17 can be opened for full capacity.

When it is desired to insert instruments, for instance a bomb 27, into the well the master valve 2 is closed to cut off the pressure, and the valve 15 is also closed to cut off back pressure from the separator. After the closing of these valves a three way valve 28 is opened for exhausting to the atmosphere the pressure within the chamber of the housing 5. The three way valve is carried by a dome 29 bolted to the upper side of the housing and then the dome 29 is removed and replaced by a fitting 30 as shown in Figure 6, that is after the bomb 27 has been

placed in the device. The bomb 27 is carried by a shooter line 31 which extends upwardly over a sheave 32, hence it will be seen that the bomb or other instrument may be lowered into the well. When the instrument is removed from the well, the dome 29 with its pressure gauge 32 is replaced on the housing 5 and the valves 2 and 15 again opened for operating purposes. Of course the needle valve 17 is retracted to the dotted line position shown in Figure 1 for the instrument inserting operation. It will be noted that the ports 12, 11, 10 and 10a are in alinement, hence instruments may be easily inserted through the plug in a transverse direction.

From the above it will be seen that a multiple choke valve is provided, simple in construction, one wherein the maximum capacity may be obtained in a single valve or any fractional part combinations thereof may be obtained. It will also be seen that means is provided in connection with the device whereby instruments may be inserted in the well transversely through the choke valve.

The invention having been set forth what is claimed as new and useful is:

1. A choke valve comprising a housing having a chamber therein, means for attaching said housing to a pressure supplying line, a plug in the chamber of said housing and having a plurality of longitudinally extending ports circumferentially arranged and extending entirely through the plug, said plug having a transverse bore registering with alined ports in the housing and communicating with an axial port extending through the plug, a cover plate for said housing,

5 a master needle valve cooperating with a seat in the axial port to one side of the transverse bore, a closure member for one of the alined ports in the housing and a plurality of different size valves carried by the cover plate and cooperating with the concentrically arranged ports.

2. A device as set forth in claim 1 wherein the master valve is retractable to a position out of alinement with the transverse bore.

10 3. A device as set forth in claim 1 wherein the concentric ports are of fractional size in relation to the axial port.

4. A device as set forth in claim 1 wherein the port controlled by the master valve is of maximum capacity size to carry the full capacity of said pressure supply line.

20 5. The combination with a multiple choke valve having a plug in the chamber thereof and a plurality of valve controlled ports extending through the plug longitudinally, said plug being disposed in a housing carried by a well pipe, of transversely alined ports carried by the housing, plug and well pipe and forming means for allowing the insertion of an instrument into the well pipe through the housing and plug and a cover member 25 removably mounted over the upper transverse port of the housing.

6. A device as set forth in claim 1 including valve seats carried by the plug ports for the said valves, said cover plate having stuffing boxes through which the valve stems extend and means whereby said valves and valve stems can be axially moved.

AUBREY L. STEWART.
